UNITED STATES PATENT OFFICE.

OSCAR J. HAGSTROM, OF BERWYN, ILLINOIS.

COMBINATION STOP-ACTION FOR ORGANS.

1,253,685.

Specification of Letters Patent. Patented Jan. 15, 1918.

Application filed June 2, 1917. Serial No. 172,384.

To all whom it may concern:

Be it known that I, OSCAR J. HAGSTROM, a citizen of the United States, residing at Berwyn, in the county of Cook and State of Illinois, have invented certain new and useful Improvements in Combination Stop-Actions for Organs, of which the following is a specification.

This invention relates to combination stop actions for pipe organs, and the main object thereof is to provide a reliable, efficient and improved apparatus of the class specified characterized by simplicity, compactness and ease of manipulation.

Other objects and advantages secured by the invention will be apparent to those skilled in the art from the following detailed description taken in connection with the accompanying drawings forming a part of this specification wherein I have illustrated one practical and workable embodiment of the invention, and wherein—

Figure 1 is a perspective elevation of a partly diagrammatic character of a combination stop action containing my present improvements.

Fig. 2 is a detail view in front elevation on an enlarged scale of one of the shiftable tappets and a fragment of an oscillatory rod on which it is mounted.

Fig. 3 is an edge view of Fig. 2.

Fig. 4 is a vertical section on the line 4—4 of Fig. 1 illustrating diagrammatically the manually controlled mechanism for connecting up and actuating the individual yokes pertaining to the several stop combinations through the agency of which the combinations of stops are first set up and later drawn on.

Fig. 5 is a sectional detail of a circuit closer, on the line 5—5 of Fig. 4.

Figs. 6 to 12 inclusive are a series of detail diagrammatic views illustrating consecutive relative positions assumed by a yoke, a tappet actuated by said yoke, and the rod on which that tappet is mounted when the stop pertaining to that rod is drawn in a combination controlled by that yoke.

Figs. 6^a to 12^c inclusive are a similar series of detail diagrammatic views illustrating consecutive relative positions simultaneously assumed by another yoke, the same rod, and another tappet on the same rod co-operating with said other yoke, when the same stop is not drawn in the combination controlled by said other yoke.

Referring to the drawings, A, A¹, A² and A³, etc., designate a series of tablets or stop keys that are a common adjunct of any pipe organ and of which there may be, of course, any desired number. These tablets are mounted side by side, so as to be capable of independent up and down rocking or swinging movement on a stationary rod or shaft 12. The organ stops controlled by these tablets are not shown, but in this instance they are electrically operated by circuits which are closed and opened by the engagement and disengagement of a circuit make-and-break pin 13 carried by each tablet with the circuit wires 14. When the tablet is raised, as shown in Fig. 1, the circuit is broken. When the tablet is depressed, the circuit through the stop-operating mechanism controlled by that tablet is established. Each tablet is controlled by a spring, partly shown at 15, in a well known manner, the spring maintaining the tablet in either raised or lowered position when moved to that position.

Connected to the respective tablets are a series of oscillating rods B, B¹, B², B³, B⁴, etc., that are supported near their ends in a bearing strip 16 and a similar strip (not shown) on the other side of the group of yokes shown in Fig. 1 and later described. On each of these rods is mounted a group of spaced tappets designated by b, b¹, b², b³, b⁴, etc. Referring to Figs. 2 and 3, it will be observed that each of the rods B, B¹, etc. (which are all alike) is not round in cross-section, except at its bearings in the supporting strips 16, but has a substantially half round side 17 and a flattened side 18 formed with a central longitudinal rib or ridge 19. The tappet, as herein shown, comprises a flat strip 20 that lies crosswise of the flattened side of the rod, and a spring backing or clamping member 21 that embraces the half round side of the rod and is secured to the strip 20 by screws or rivets indicated at 22. Each tappet is thus mounted on the rod with sufficient friction to prevent it from sliding on or lengthwise of the latter, but the backing or clamping member 21 has sufficient elasticity to permit the tappet to be shifted, under the application of sufficient force, around the rod between two positions in which it bears on the central rib 19 and the opposite edges respectively; Figs. 6 and 8 illustrating these two relative positions of the tappet and rod.

As will appear later, however, in the description of the operation, the tappet hugs the rod with sufficient tightness to enable it, when itself actuated by the yoke, to rock the rod and swing the tablet to "on" or "off" position, thereby making or breaking the electric circuit of the stop-operating mechanism. Each rod has an offset crank portion 51 that is connected by a link 52 to 10 a forwardly projecting arm 53 on one of the tablets.

Disposed transversely of the rods are a series of parallel yokes C, C¹, C², C³, C⁴, etc. that are supported with capacity for end- 15 wise sliding movement on cross-bars 23 shown in Fig. 4 but omitted from Fig. 1 for the sake of clearness. The rods B, B¹, etc. extend through these yokes, and the upper and lower bars of each yoke overlie and 20 underlie respectively a group of tappets. Depending from the upper bar of each yoke is a series of pins or lugs 24, and upstanding on the lower bar in line with the pins or lugs 24 is a corresponding series of pins or lugs 25. These pins normally lie a slight distance behind the tappets, viewing Fig. 1. Pivotally connected to one end of each yoke is a link 26 terminating at its free end in an upstanding hook 27. The links 26 normally 30 rest on the upper edge of a supporting strip or plank 28, and are guided in their up and down movements by pins 29. Beneath each link is a lifter-rod 30, the lower end of which is connected to the movable side of a pneumatic 31 housed within a wind-chest 32, the pneumatic being capable of being vented to the atmosphere through the agency of an electro-pneumatic valve device indicated at 33 and controlled by a normally open circuit 35 including the wires 34 and 35 leading from opposite poles of a suitable current generator (not shown). The ends of the circuit wires 34 and 35 are connected to spring terminals 34' and 35' (Fig. 5) supported in a block 36 of insulating material, and the circuit is closed when required by a spring-retracted 40 circuit closer or switch 37 that is carried on the inner end of a plunger or push button 38 located within convenient reach of the 45 organist when playing the instrument. It will be understood that there are as many of these electrically controlled pneumatic hook-raising devices as there are combination setting and drawing devices in the combination 50 stop action,—that is, there is one for each hook and its connected yoke; and in Fig. 1 I have numbered the several plungers or 55 push-buttons 38 as 1, 2, 3, 4, 5, etc., indicating the successive combination setting and 60 drawing devices controlled thereby.

39 designates a bar supported on arms 40 from a rock-shaft 41. Fast on rock-shaft 41 is an arm 42 connected by a link 43 to one end of a lever 44 that is mounted on a 65 shaft 45. The other end of lever 44 carries

a roller 44' that rests on the movable side of a pneumatic 46 mounted on a wind-chest 47. The admission and exhaust of air to and from the pneumatic 46 through the wind-chest 47 is controlled by an electro-pneumatic valve indicated at 48. Since this mechanism, like that controlling the pneumatic 31, is old and well known in the art, it is thought to be unnecessary to encumber this specification with a detailed description 70 of the same. The valve device 48 is controlled by a normally open circuit including the wires 34, 35 and 49. One end of wire 49 is connected to wire 35 at 50 and its other end is connected to a spring terminal 49' that is mounted in the block 36 alongside of the terminals 34' and 35'. It will be observed that the upper end of terminal 49' is bent outwardly or away from the circuit closer 37; so that when the plunger 38 is 85 pressed inwardly, the circuit through the magnet 33 is first closed, raising one of the hooks 27 across the path of swing of bar 39, and later, on the same inward movement of the plunger, the circuit through magnet 48 is closed, swinging the bar 39 to the left in Figs. 1 and 4, and thus imparting an end-wise movement in the same direction to the yoke whose hook has been raised. It will be understood, of course, that the magnet 90 48 is wired to each and all of the several circuit-closers 1, 2, 3, 4, 5, etc. Each yoke is normally held at the right hand limit (Figs. 1 and 4) of its movement by a spring 95 54 and stop-bar 55, and is returned to that 100 position by spring 54 the instant the pneumatic 46 is deflated by the opening of the circuit controlling the same.

In the normal idle or "cleared" position of the action, all of the hooks 27 are down and all of the tappets are upright or vertical and occupy the relative positions on and to their respective rods shown, for example, in Figs. 6 and 6^a. To set any stop in a given combination, say that controlled 105 by tablet A in the first combination controlled by the yoke C, the plunger 38 (No. 1) is first pushed in. This raises the hook 27 of yoke C and an instant later rocks bar 39, drawing yoke C to the left, from the position shown in Fig. 6 to that shown in Fig. 7. Still holding the plunger depressed, the organist with the other hand depresses tablet 110 A. This rocks the rod B, but since the tappet b is held by the pins 24 and 25 of the 115 yoke against movement, the rod turns in the fastening strap or clamp of the tappet to the position shown in Fig. 8. The plunger is then released and the tablet raised to normal or "off" position. This rocks the 120 rod B back to its former position, and tilts the tappet b to the inclined or "set" position shown in Fig. 9 and at the same time spring 54 returns the yoke C to the right. Other 125 stops used in the same combination, and other 130

combinations controlled by the yokes C^1 , C^2 , C^3 , C^4 , etc., and by the tablets or stop keys A^1 , A^2 , A^3 , etc., are set up in the same way. Fig. 1 illustrates five combinations as set

5 up, the first combination including the stops controlled by tablet A^1 and the next tablet (not shown) beyond tablet A^3 , the second those controlled by tablets A^1 and A^2 , the third those controlled by tablets A and A^2 , the fourth those controlled by tablets A^1 and A^3 , and the fifth those controlled by tablets A , A^1 , A^3 and the next tablet beyond A^3 . It is evident that these combinations may be drawn on successively by merely 10 pressing the push-buttons or plungers 1, 2, 3, 4 and 5 pertaining thereto, a pin 24, as the yoke moves to the left, striking the upper end of the inclined tappet (Fig. 9) and swinging it to vertical position as shown in Fig. 10 which action at the same time rocks the rod, depresses the tablet, and 15 draws on the stop. Any stop used in one combination but not used in a succeeding or later combination is automatically drawn off when such succeeding or later combination is drawn on. This is illustrated in Figs. 20

25 6 to 12 and 6^a to 12^a, where it may be assumed that the stop controlled by tablet A is used in the first (yoke C) combination but is not used in the second (yoke C') combination. When the stop is drawn on by yoke C (Fig. 10), the tappet b^1 , belonging to the second combination, is shifted to the inclined position shown in Fig. 10^a, so that when yoke C^1 is operated to draw the second combination, pin 25, acting on the lower 30 end of tappet b^1 , draws the stop controlled by tablet A to off position (Fig. 11^a), which at the same time returns tappet b to the position shown in Fig. 11.

40 When through playing, the action may be "cleared" by depressing all the tablets that have been used in the stop combinations, pressing the plungers 38 of the combinations that have been used, then raising said tablets while holding the plungers in circuit-closing position, and then releasing the plungers which restores the parts to the normal position shown in Fig. 12 which is the same as that of Fig. 6.

45 While I have shown electro-pneumatic mechanism for setting and drawing the combinations it should be understood that this is not of the essence of the invention, since electrical, pneumatic, or mechanical means alone might be used without affecting the operation of the cooperating parts of the combination stop action itself.

50 It is believed that the construction, mode of operation, and advantages of my improved combination stop action will be clear to organ builders and others skilled in the art without further detailed description. It will be understood that many of the parts of the mechanism are shown more or less 55 diagrammatically and that such parts will

be subject to such variations as may be desirable to conform to the limitations of individual installations. I therefore do not wish to be limited to the exact mechanism shown and described but claim all equivalents thereof which come within the spirit of the invention as defined in the appended claims. 70

I claim:

1. In a combination stop action for organs, the combination of a series of bars mounted for endwise movement and provided with transversely projecting lugs, a series of stop keys, a series of rods extending across said bars and mounted for oscillating movement about their longitudinal axes, connections between said stop keys and said rods, whereby a stop key will operate its rod or be operated thereby at will, and tappets mounted on and transversely of said rods and in the paths of travel of said lugs, said tappets engaging their respective rods with sufficient friction to operate said stop keys when struck by the lugs of said bars, but capable of being shifted angularly about 90 said rods. 75

2. In a combination stop action for organs, the combination of a series of yokes each including upper and lower parallel bars mounted for endwise movement, alined depending and upstanding lugs on said upper and lower bars respectively, a series of stop keys, a series of rods extending through said yokes and mounted for oscillating movement about their longitudinal axes, 95 connections between said stop keys and said rods whereby a stop key will operate its rod or be operated thereby at will, and tappets mounted on and transversely of said rods within said yokes, said tappets engaging 100 their respective rods with sufficient friction to operate said stop keys when struck by either the depending or upstanding lugs of said yokes, but capable of being shifted angularly about said rods. 105

3. In a combination stop action for organs, the combination of a series of stop keys, a series of oscillating rods connected to said stop keys respectively, angularly shiftable tappets frictionally mounted on 110 and transversely of said rods, endwise movable members mounted transversely of said rods and adapted to oscillate the latter through engagement with said tappets, hooks pivotally connected to said endwise 115 movable members respectively, an actuating bar mounted transversely of said hooks and normally in disengaged relation to the latter, means for shifting said hooks independently into the path of said bar, and means for actuating said bar. 120

4. In a combination stop action for organs, the combination of a series of stop keys, a series of oscillating rods connected to said stop keys respectively, angularly 125

shiftable tappets frictionally mounted on and transversely of said rods, endwise movable members mounted transversely of said rods and adapted to oscillate the latter through engagement with said tappets, hooks pivotally connected to said endwise movable members respectively, an actuating bar mounted transversely of said hooks and normally in disengaged relation to the latter, means for shifting said hooks independently into the path of said bar, means for actuating said bar, and a manually operable device serving during the first part of its working movement to energize said hook-shifting means and during the latter part of its movement to energize said bar-actuating means.

5. In a combination stop action for organs, the combination with a stop key operating rod having a substantially half-round side and a substantially flat side

formed with a central longitudinal rib, of a tappet lying crosswise of said flat side, and spring means normally holding said tappet engaged with said rib and one margin of 25 said flat side, but permitting said tappet to be shifted by a relative turning movement into engagement with said rib and the other margin of said flat side.

6. In a combination stop action for organs, the combination with a stop key operating rod having a substantially half-round side and a substantially flat side formed with a central longitudinal rib, of a tappet lying crosswise of said flat side, 35 and a spring clamp secured to the back side of said tappet and embracing the half round side of said rod and holding said tappet yieldably engaged with said rib and one margin of said flat side.

OSCAR J. HAGSTROM.
